J. G. R. O'HARA,
MOTION PICTURE PROJECTING MACHINE,
APPLICATION FILED JUNE 8, 1918.

1,308,444.

Patented July 1, 1919.

Inventor

Joseph G.R. O'Hara

By *J. G. O'Hara, Jr.*

UNITED STATES PATENT OFFICE.

JOSEPH G. R. O'HARA, OF ST. LOUIS, MISSOURI, ASSIGNOR TO EDUCATIONAL MOTION PICTURE MACHINE AND FILM COMPANY, OF ST. LOUIS, MISSOURI, A CORPORATION OF MISSOURI.

MOTION-PICTURE-PROJECTING MACHINE.

1,308,444.

Specification of Letters Patent.

Patented July 1, 1919.

Application filed June 8, 1918. Serial No. 239,024.

To all whom it may concern:

Be it known that I, JOSEPH G. R. O'HARA, a citizen of the United States, residing at the city of St. Louis, State of Missouri, have 5 invented a certain new and useful Improvement in Motion - Picture - Projecting Machines, of which the following is a full, clear, and exact description, such as will enable others skilled in the art to which it applies 10 pertains to make and use the same, reference being had to the accompanying drawings, forming part of this specification, in which—

Figure 1 is a side elevational view of my 15 improved motion picture projecting machine.

Fig. 2 is a detail sectional view of the mechanism connected with the shaft and of the winding reel.

Fig. 3 is a detail sectional view of the 20 other end of the driving shaft for the winding reel.

Fig. 4 is a horizontal cross section through the housing and showing means of mounting the housing in the guide.

This invention relates to a new and useful improvement in motion picture projecting machines, the object being to simplify the construction of such machines and to 30 positively drive the winding shaft in all positions of the machine.

In the drawings, 1 indicates the base, 2 the lamp housing or casing mounted thereon. 3 is the lens tube fixed to the base 1, 35 as is also the lamp housing 2. 4 is the housing containing the mechanism operated by the handle 5 for unwinding the film from the reel 6 mounted on the housing 4 and winding said film onto winding reel 7. The

40 housing 4 is mounted in suitable guides on the base 1 and capable of vertical movement relative thereto, said housing having a rack 8 with which meshes a pinion 9 arranged on the shaft mounted in the bearings on the base 1. Pinion 9 is connected to a handle 10 provided with a detent 11 which latter co-operates with a ratchet 12 fixedly secured to the base 1. The detent 11 has a thumb piece 11^a connected thereto and arranged ad-

45 jacent the handle 10 which handle 10 is conjoined to the pinion 9, whereby when the handle is adjusted in its rotative positions, the casing 4 is likewise adjusted. This adjustment of casing 4, which carries the op-

erating mechanism for the film, is necessary 55 to "frame" the projected picture.

As the winding reel 7 is operated from the mechanism contained within the housing or casing 4, I provide a shaft 13 operated by the mechanism in casing 4 and extending through a suitable packed joint in the wall of the casing 4, said shaft 13 having a collar 14 pivotally connected with a sleeve 15 by means of suitable pivot pins forming the universal joint. Sleeve 15 has 60 a slot and pin connection with a shaft 16 which latter has a collar 17 connected by a universal joint to a shaft 18, the latter carrying a miter gear 19 meshing with a corresponding gear 20 loosely mounted on shaft 70 21. This shaft 21 is arranged in a bracket 22 secured to the base frame and by means of a spring 23, the miter gear 20 is in frictional engagement with the collar 24 pinned to the shaft 21. Thus the winding shaft 75 21 may be frictionally driven, its speed of course being predetermined so as to compensate for the difference in the diameter of the film as it is unwound from the feeding reel 6 to the winding reel 7. 80

Whenever it is desired to "frame" a picture, the handle 10 is adjusted to the proper position and upon the release of finger piece 11^a is locked in such a position. The turning of the handle 5 will wind the film 85 onto the receiving reel 7 and by virtue of the universal joint connected to the shaft 16 and the slot and pin connection permitting the longitudinal movement of said shaft in the sleeve 15, the shaft 16 and consequently the winding reel 7 will be driven at the same predetermined speed in any adjusted position of the gear casing. 90

I am aware that the motion picture projecting machine illustrated and described is 95 susceptible of various alterations, changes, modifications and adaptations not specifically referred to or disclosed, but comprehended, nevertheless, within the spirit of the invention and the scope of the appended 100 claims.

I claim:

1. In a motion picture projecting machine, the combination of a base, a gear housing 105 adjustably mounted thereon for "framing" the picture, said housing providing a bearing for the driving shaft, and a receiving reel driven by said shaft, said shaft hav-

- ing universal joints and telescopic connection whereby the receiving reel may be driven at a predetermined speed in any position of the gear housing.
- 5 2. In a motion picture projecting machine, a base, a shaft journaled in a part of said base, a receiving reel carried by said shaft, a gear housing arranged for vertical movement upon the base, a driving shaft connected with the gearing within said housing and extending to the shaft carrying the

receiving reel, said driving shaft being extensible and provided with universal joints, a rack carried by the gear housing, a pinion journaled on the base and coöperating with said rack, a hand lever for actuating said pinion, and means for locking said hand lever in its adjusted positions.

In testimony whereof I hereunto affix my signature this 3rd day of June, 1918.

JOSEPH G. R. O'HARA
